PREVENTION OF REVERSE FLOW IN WATER SUPPLY SYSTEMS

Louis Irving Norton, Washington, D. C.

Application February 2, 1940; Serial No. 317,020

5 Claims. (Cl. 137—79)

The present invention relates to improvements in water supply systems and has reference more particularly to an arrangement for preventing the flow of liquid in other than the designed direction and thereby preventing back siphonage and reverse flow from occurring.

This application is a continuation in part of my copending application, Serial Number 137,232, filed April 16, 1937, now Patent No. 2,205,305, granted June 18, 1940.

One of the important objects of the present invention is to provide an arrangement which will prevent back siphonage, irrespective of pressure variations and conditions that may occur in the water supply system, and further without the use of any mechanical means or moving parts.

A still further object of the invention resides in the provision of an arrangement of the above mentioned character which can be readily and easily installed in a water supply system without necessitating any material alterations in the system, and which will at all times be positive and efficient in carrying out the purposes for which the same has been designed.

An important, though not the only application of the invention will be in conjunction with water supply systems. When applied to such systems, my invention will prevent reverse flow and back siphonage from cross connected plumbing fixtures, etc., through supply branches toward the supply riser.

According to the present invention, means is provided to prevent the occurrence of any substantial sub-atmospheric pressure (vacuum) in water supply risers, etc. This arrangement is to be distinguished from arrangements in which atmospheric air is introduced only after the occurrence of a partial vacuum, or of a vacuum at its critical pressure, and, therefor, after back siphonage has or could have occurred, as where unreliable vacuum breakers and the like are employed. For accepted formula of critical pressure of vacuum, see my Patent No. 2,205,305, page 2, lines 70 to 74, inclusive.

Other objects and advantages of the present invention will become apparent from the accompanying drawings and the following description.

In the drawings, wherein like reference characters designate corresponding parts:

Figure 1 represents a schematic representation of a part of water supply system (riser and supply branches) embodying the invention, and

Figure 2 is a similar schematic representation of a part of a water supply system indicating

the usual and customary practice of installation of the riser and branches, with the addition of a liquid seal for the uppermost receptacle.

In the drawings, with reference more particularly to Figure 1, the numeral 8 designates the usual riser which supplies water in any up-feed or in any down feed water supply system, to the branches leading to various discharge outlets and plumbing fixtures located on the various floors of a building. In accordance with building construction and design conditions, the various supply branches are usually located below the finished ceiling or in the floor, in order to avoid door or window crossings with such supply branches.

It is also known in practice, that a supply riser may supply the water to two bath rooms or kitchens, especially when the riser is located in the partition between two dwellings. In such instances, the supply branches are doubled on each floor in order to supply hot and cold water to both dwellings.

A liquid seal, shown generally at 1, is associated with the upper open end 9 of the riser 8 and is more specifically disclosed in my application, Serial Number 137,232. The liquid seal 1, includes a shell or jacket 11 that surrounds the upper end portion of the riser 8 in spaced relation thereto, the lower end of this shell or jacket being connected to the adjacent portion of the riser to provide a closed bottom for said jacket. The upper end of this shell or jacket is open and extends above the open upper end of the riser and has a vent pipe or opening 10 extending upwardly therefrom for supplying air to the seal and riser 8, when the pressure, due to various reasons, ceases in the riser.

The uppermost receptacle 5 represents any plumbing fixture and the conduit or branch 2 affords communication between the lower portion (discharge outlet) of the liquid seal 1 and the receptacle 5. The height of the maximum water level of the receptacle 5 above the conduit or branch 2 is indicated in the drawing by "hr" and the top end of the submerged supply riser (submerged in the liquid seal 1) is indicated by "hi."

Since the top of the submerged riser in the liquid seal 1 is considerably higher than the maximum height of the water level of the receptacle 5, consequently, the top of the submerged riser 8 can never be overflowed with water in case of a total pressure drop in the supply riser.

From the foregoing, it is clearly seen that when a total pressure drop occurs in the riser 8,

consequently first, at the top of the submerged riser, due to the height of the water column in shell 11, a positive pressure must exist at the bottom of branch 2 that is directly connected to the outer shell of the liquid seal 1. This height being in excess of " h_R " therefor, due to prevailing hydrostatic pressure, flow must occur through supply branch 2 toward the receptacle 5. The excess pressure created by the constant height of the liquid seal is indicated by " h_2 ," or the excess pressure $h_2 = h_1 - h_R$.

In case of a partial or a total pressure drop, the supplied atmospheric air is present in the extended part of the air supply pipe 10 (air inlet or air supply opening) and when the pressure ceases in riser 8, the down falling water column will be followed by the supplied atmospheric air. The direction of flow of the atmospheric air is indicated by the arrows and the atmospheric air itself exerts its pressure on the surface of the water in the various receptacles, just the same as the same atmospheric pressure exerts its pressure on the surface of water in water seal 1 at the height marked, " h_R ," thereby creating the absolutely necessary pressure equilibrium.

The velocity of the atmospheric air flow is always the same as the velocity of the down falling water column in the riser 8. The water must evacuate the riser first, and only then, can the inflowing atmospheric air replace the water in the riser in order to create atmospheric air conditions in the riser, thereby preventing such vacuum formations, which vacuum would ever be able to lift up the water column " h_1 ." Since in a case of a total pressure drop the maximum height of the water line " h_R " in shell 11 is entirely separated from the riser 8 by the outer shell 11 of the water seal 1, therefore an entirely free air supply port is secured at the open upper end 9 of the riser and the atmospheric air will flow freely into the submerged riser 8 regardless of the source of the supplied atmospheric air.

At the same time the supplied atmospheric air will exert its pressure on the surface of the water in the shell or jacket 11 of the water seal and the same atmospheric pressure will exert its pressure on the surface of the water in the receptacle 5. This will result in the pressure conditions being placed in equilibrium, hence no vacuum formation, much less back siphonage will or could occur in the upper part (top floor) of the water supply system.

In order to secure the same safe water supply conditions at the lower floors of a building, it is necessary to install at each floor, a branch supply conduit in the form of a loop, designated at 3-B which extends from the riser 8 to one end of the horizontal supply pipe 3, the other end of this pipe 3 having communication with a receptacle 7.

An auxiliary supply pipe 6 extends upwardly from the horizontal supply pipe 3 and supplies water to other plumbing fixtures (not shown).

In Figure 1 of the drawings, I have illustrated the arrangement for one of the lower floors and the same arrangement of piping is employed with all of the other lower floors.

The auxiliary supply pipe 6 being in the instant case, the highest branch of the supply pipe 3, therefore the loop 3-B must be higher than the height of the auxiliary supply pipe 6. The height of the loop or branch supply conduit 3-B is indicated by " h_4 " and the height 75

of the auxiliary supply-pipe 6 is designated by " h_1 ." The water column in excess to " h_1 " is indicated by " h_2 ." It will thus be seen that the height of the loop or branch supply conduit 3-B is equal to " h_1 " plus " h_2 ."

The hydrostatic pressure head created by the height of the branch supply conduit or loop 3-B, above the normal water level in the receptacle 7 is greater than the maximum suction that is possible to be produced at the point of communication of the upper end of the conduit or loop 3-B with the riser 8.

Considering the very fact that the pressure being always the smallest at the top floor, in any up-feed or down-feed riser, consequently the pressure will cease at the top floor first, and only after this will the pressure gradually cease at the lower branches in case of a total pressure drop regardless of the cause of its occurrence (shutting off the main or overloaded or corroded supply riser, poor pressure conditions, etc.). In the referred case of a total pressure drop the prevailing hydro-static pressure between floors will cause a flow toward the supply pipe 3 and downward in riser 8 depending on the size of riser and size of supply pipes at the lower floors, and depending also on the rate of flow, in this case on rate of reverse flow.

In a case of a total pressure drop the down falling water column will be followed by the atmospheric air passing through extended air pipe 10 or through atmospheric air supply inlet into the riser 8, and as stated before, always with such velocity as the velocity might be of the down falling water column in riser 8. The branch supply conduit 3-B as indicated, being considerably higher than the auxiliary supply pipe 6 and higher than the maximum water-line in receptacle 7 therefor, the supply-branch outlet connected to riser 8 must be always free from the slightest obstruction and due to this the inflowing atmospheric air will exert its pressure on the surface of water in branch supply conduit 3-B just the same as the same atmospheric pressure exerts its pressure on the surface of the water in receptacle 7 and in auxiliary supply pipe 6 which might be open to atmosphere due to an open faucet, etc.

If the water column in the riser 8 drops with a velocity which is sufficient to create suction at the inlets to the respective several branch conduits, the head of the water column in the liquid seal 1 and the loop 3b is arranged to be of a sufficient height to prevent reverse flow from such inlets into the riser. The friction and resistance which would be produced if there were any reverse flow could also be taken into consideration in determining the necessary heads of water columns in the seal and loop.

The air pipe 10 can enter into an air supply header which again ends at such place at the upper part of the building where an unobstructed free air supply can be easily secured or pipe-line 10 might end into a well protected air-supply inlet head protected with a carefully secured and enlarged wire screen having at least four times as large cross section as the pipe-line 10 in order to eliminate the slightest resistance at the source of atmospheric air supply, as shown in my prior Patent No. 2,205,305. Of course, the applied method of atmospheric air supply into riser 8 depends entirely on local building and prevailing pressure conditions, namely, the method of atmospheric air supply into the riser

8 is entirely different from a riser which ends at the fifth floor of a thirty (30) story high building or the riser 8 ends at the thirtieth floor of the same building, or is the top of the riser (pipe 10 of the water seal of Figure 1), occasionally below or above the prevailing pressure zone. The height of the conduit 3-B is to be determined by local conditions when the height and volume of riser 8 has to be considered and also the maximum velocity of the down falling water column (based on the Newton theorem) in a case of a total pressure drop in riser 8 especially, when the riser 8 has to be drained, in which case the velocity of the down falling water column might reach its maximum velocity), and so the velocity of the inflowing atmospheric air.

The purpose of Fig. 2 is to clarify the pressure and airflow conditions at the lower floors of a riser 4, which is provided with a water seal at the top outlet of the riser 4, in order to eliminate the remotest possibility of reverse flow from any plumbing fixtures, etc., supplied with water through the water seal 1. Installing a water seal at the top floor will create that hydrostatic pressure in shell 11 in a case of a total pressure drop, which hydrostatic pressure is absolutely necessary to create flow toward the connected plumbing fixtures, like receptacle 5 and eliminate the reverse flow from the same through supply branch 2 toward riser 4, and by this result the prevention of infection and pollution of the water supply system has been successfully prevented.

Installing a well protected water supply piping at the top floor as this is indicated on Fig. 2 by using the water seal 1 does not prove yet that the same prevention of reverse-flow has been successfully established nor achieved at the lower floors of the same riser 4, or any other riser in the same building regardless that those risers are supplying hot or cold water for human consumption.

According to the standard piping practice in buildings the supply branches at the lower floors are arranged in the floor construction, concealed in order to eliminate door and window crossings, as is clearly indicated in Fig. 2. The supply-branch 3 supplies the receptacle 7 with hot or cold water and the auxiliary supply pipe 6 which leads, as usually to a shower or to any other plumbing fixture (not shown). The height of the maximum water-line of receptacle 7 is indicated by " h_3 " and the height of auxiliary supply-pipe 6 and maximum water level is indicated by " h_4 ." In a case of total pressure drop in riser 4, the hydrostatic-pressure existing between the top of riser 4 and between the supply branch (takeoff) 3 will cause a flow of water toward the receptacle 7 and auxiliary supply pipe 6. This flow will continue until the motive power of flow, namely, the previously referred hydrostatic-pressure exists between the upper and lower supply pipes, for example, between the submerged top of the water seal 1 and between supply-branch 3.

When the conditions of the system are such that there is a down falling water column, there may be created at the inlets to the branch take-offs, such a velocity of flow that a pressure below atmosphere will exist at such points.

In order to prevent reverse flow into the riser from the branches as a result of such sub-atmospheric pressure at the take-offs, a head of water is provided between the riser 8 and the

branches which is greater than the greatest possible sub-atmospheric pressure at the take-offs. Of course, in determining such necessary heads, consideration may be given to pressure drop due to friction and resistance existing in the branches and their take-offs.

Having thus described my invention, what I claim is:

1. In a vertical water supply system, wherein a plurality of receptacles having a normal liquid level, are disposed at different levels and connected to a common liquid supply riser, means for supplying liquid to those receptacles below the uppermost receptacle including a branch leading into each receptacle from the supply riser from a point in said supply riser above the normal liquid level in each receptacle, the height of the branch above the normal liquid level in said lower receptacle being such as to produce a head greater than the maximum suction head capable of being produced by the velocity of flow of fluid in the riser at the point of take-off connection between the branch and the riser, a shell surrounding and spaced from the upper portion of the riser and communicating at its upper end with the atmosphere and closed at its lower end, a branch connecting the uppermost receptacle with the shells, the upper end of the supply riser being open and extending above the normal liquid level in the uppermost receptacle, the height of the riser above the upper receptacle being sufficient to create a head of liquid in the shell capable of preventing reverse flow from said last mentioned branch to the shell as a result of a maximum drop in pressure in the riser at the point of take-off of said branch due to velocity flow of fluid past said take-off.

2. In a vertical water supply system embodying a plurality of receptacles having a normal liquid level, adapted to be supplied and wherein the receptacles are disposed at different levels, a liquid supply riser, closed branches leading respectively from said riser to each of the lower receptacles from a point substantially higher than the highest normal liquid level in each of the lower receptacles, the height of the branches above the normal liquid level in each of said lower receptacles being greater than the maximum suction head capable of being produced by the velocity of flow of fluid in the riser at the point of take-off connection between the branches and the riser, a branch connecting the uppermost receptacle with the supply riser, the upper end of the riser being open and extending above the normal liquid level in said uppermost receptacle, and a liquid seal for the last mentioned branch including a surrounding spaced shell about the open upper end portion of the riser, said shell having its upper end venting to the atmosphere, the lower end of the shell being closed, said last mentioned branch having communication with the lower portion of the shell, the height of the riser above the normal liquid level in the uppermost receptacle being sufficient to create a head of liquid in the shell capable of preventing reverse flow from the last mentioned branch to the shell as a result of a maximum drop in pressure in the riser at the point of take-off of said branch due to velocity flow of fluid past said take-off, whereby reverse flow of the liquid into the riser from the receptacles is prevented.

3. In a vertical water supply system, wherein a plurality of receptacles having a normal liquid level are disposed at different levels and connected to a common liquid supply riser, means

for supplying liquid to those receptacles below the uppermost receptacle including a branch leading into each receptacle from the supply riser from a point in said supply riser above the normal liquid level in each receptacle, a shell surrounding and spaced from the upper portion of the riser and communicating at its upper end with the atmosphere and closed at its lower end, a branch connecting the uppermost receptacle with the shell, the upper end of the supply riser being open and extending above the normal liquid level in the uppermost receptacle, the height of the riser above the upper receptacle being sufficient to create a head of liquid in the shell capable of preventing reverse flow from said last mentioned branch to the shell as a result of a maximum drop in pressure in the riser at the point of take-off of said branch due to velocity flow of fluid past said take-off, the vertical distance of each of the first mentioned branches above the normal liquid level of their associated receptacles and their point of connection with the riser as well as the height of the riser above the uppermost receptacle being equal to a head sufficiently higher than the head produced by the maximum suction capable of being produced at each branch connection as a result of any pressure drop in the riser, minus the head due to pressure drop caused by friction and resistance in the branches if reverse flow could occur therein, whereby reverse flow of liquid back to the supply riser is prevented.

4. In a water supply system embodying a plurality of receptacles having a normal liquid level, and wherein the receptacles are disposed at different levels, a liquid supply riser having its upper end in communication with the atmosphere, means for delivering liquid from the supply riser to said receptacles including branches, each of the receptacles including a back siphon-

age prevention means, the back siphonage prevention means for any selected receptacle being formed by arranging the branch so as to lead from the supply riser at a point substantially higher than the normal liquid level in the selected receptacle, the effective height of each branch from its connection between the riser and the normal liquid level of its associated receptacle being sufficient to overcome the maximum suction head capable of being produced by the velocity of fluid passing the point of take-off connection between the riser and the branch for such receptacle due to pressure drop in the riser, whereby reverse flow of liquid back to the supply riser is prevented.

5. In a water supply system embodying a plurality of receptacles having a normal liquid level, and wherein the receptacles are disposed at different levels, a liquid supply riser having its upper end in communication with the atmosphere, means for delivering liquid from the supply riser to said receptacles including branches, each of the receptacles including a back siphonage prevention means, the back siphonage prevention means for any selected receptacle being formed by arranging the branch so as to lead from the supply riser at a point substantially higher than the normal liquid level in the selected receptacle, the vertical distance of each branch above the normal liquid level of its associated receptacle and its point of connection with the riser being equal to a head sufficiently higher than the head produced by the maximum suction capable of being produced at each branch connection as a result of any pressure drop in the riser, minus the head due to pressure drop caused by friction and resistance in such branch if reverse flow could occur therein, whereby reverse flow of liquid back to the supply riser is prevented.

LOUIS IRVING NORTON.
